UNITED STATES PATENT OFFICE

2,264,446

METHOD OF PRODUCING INGOTS OF RISING
OR OPEN STEEL

Edgar Marburg, Apollo, Pa.

Application April 21, 1939, Serial No. 269,268

4 Claims. (Cl. 22—200)

This invention relates to ingot molds and, more particularly, to caps which are used to seal the tops of ingot molds of the "bottle top" type after the molten steel has been poured to a height of a few inches below the top thereof. The molten metal is usually of the "rising" or "open" type and, hence, the height to which it is poured depends somewhat upon the rate of rise. "Rising" or "open" steel has very little pipe in any case; whereas "killed" or "deoxidized" steel has considerable pipe. In "killed" steel, mold caps of non-conducting material are employed; whereas with "rising" or "open" steels it is essential to employ a mold cap of conducting material, such as cast metal. "Killed" steels would never rise into contact with caps; whereas this is a characteristic of "rising" or "open" steels.

The rise of molten metal is caused by gas evolved as the metal solidifies; and if there is considerable gas evolution, the gas pressure developed in the ingot when the cap is applied may be sufficient to lift one edge of the cap and blow out a stream of molten metal. This, of course, is a serious hazard to men working on the "pouring platform" and has been one of the principal objections to the use of caps in connection with "rising" or "open" steel.

In order to overcome this serious hazard to the workmen by "blowing-off," two widely used methods have been developed. The first of these is to employ lugs on the top of the mold and to insert a pin through the lugs and also the hole in the handle by which the heavy mold cap is manipulated. The second widely used method is to make the mold cap extremely heavy (such, for example, as 350 pounds, or more).

The method of pinning the mold cap to the top of the mold is not only troublesome in that it requires a separate operation to make sure the cap will not "blow-off," but is objectionable for the reason that the lugs in the top of the mold are often knocked off or damaged to such an extent as to be either totally inoperative or to require straightening out or some other form of repair.

The method which comprises making the mold cap very heavy is objectionable because of the difficulty in handling it.

So far as I am aware, mold caps in most general use have been of two distinct types. One type employs a rather shallow base with rounded edges and may be of light weight and pinned down, or of heavy weight and not fastened. The other type embodies a hemispherical-shaped

bottom and is usually made quite heavy and may or may not be pinned to the top of the mold.

It is among the objects of the present invention to provide a cap for ingot molds which is "self-locking" to the top thereof and yet one which is relatively light when compared with the weight of comparable devices.

It is another object to provide a cap for ingot molds which rests flat on the floor of the pouring platform immediately prior to its application to the top of the ingot mold, whereby it is easier to pick up than the type employing the hemispherical bottom which, of course, may roll in any direction.

It is another object of the present invention to provide a cap for ingot molds which will result in the formation of an ingot entailing less metal loss due to cropping.

The foregoing and other advantages will be apparent after referring to the drawing, in which:

Figure 1 is a side elevation of the ingot mold cap of my invention as applied to a conventional ingot mold of the "bottle top" type, the latter being shown in section;

Figure 2 is a view similar to Figure 1 but showing the position the mold cap of my invention would be required to occupy if a "blow-off" were to occur;

Figure 3 is a sectional elevation of my improved mold cap; and,

Figure 4 is a sectional elevation covering an ingot which has been formed by the use of my improved mold cap.

Referring more particularly to the drawing, the numeral 2 generally designates a conventional ingot mold of the "bottle top" type, having the usual opening defined by vertical walls 3.

The improved mold cap of my invention is made of cast metal and comprises a circular plate portion 5, the external diameter of which is materially larger than the diameter of the opening at the top of the mold defined by the straight walls 3. Therefore, the circular plate 5 may rest upon the top of the ingot mold 2 and completely close the opening therein. Connected to the under side of the circular plate 5 there is a base portion which comprises a continuous inverted frusto conical wall. The greatest diameter of the frusto conical base portion 6 is adjacent the circular plate 5 and is of a diameter substantially that of, although slightly larger than, the opening in the top of the mold. Therefore, the inverted frusto conical base portion 6 of the mold cap of my invention prevents the

50

seating of the circular plate 5 on the top of the mold.

Referring to Figures 1, 2 and 3 of the drawing, it will be noted that the bottom of the inverted frusto conical base portion 6 is provided with a concave recess 7. This concave recess 7 results in the shaping of the top of the ingot in the mold 2 in the manner indicated at 7^a of Figure 4 of the drawing. When shaping the ingot thusly, it will be observed that a shallow crop may be resorted to and a greatly increased portion of the ingot used than would be the case if a mold cap embodying a hemispherical or flat bottom were employed.

Referring to the arrows shown in the upper right-hand corner of Figure 2 of the drawing, it will be observed that in the event of a blow-off, molten metal must pass through a narrow opening defined by the sides of the frusto conical base 6 of the mold cap and turn at right angles along the bottom face of the circular plate 5.

Due to the slight taper on the frusto conical sides of the base 6 of the mold cap and the substantial depth of said base, the molten metal at the sides of the cap forms a thin fin around the base which solidifies rapidly and forms a strong protection in itself. This fin remains on the upper end of the ingot as shown at 7^b in Figure 4. If the mold cap of the present invention is subjected to a force pushing upward at one point in its periphery, which would tend to make it rotate around a point on the opposite side, the tendency would be for the base 6 to wedge itself even tighter against the mold neck, thus making it substantially self-locking. The only alternative would be if the pressure were exerted uniformly over the inverted frusto conical base 6 of the cap, thereby lifting it straight upward. Although the mold cap of the invention has been subjected to rather extensive trials, such straight upward lifting has never occurred; but even if it should, it can readily be seen that the condition of blowing-off a cap straight upward would be far less dangerous than the usual hazard of one side of the cap lifting and thereby allowing the molten metal to "blow-out" onto the "pouring platform." It has been found that, by projecting the inverted frusto conical base 6 of the mold cap of the invention into the ingot mold as compared with conventional practice wherein the cap does not extend into the mold more than 1½ inches, there is provided a locking feature against any rotary motion.

While I have shown and described one embodiment of my invention, it will be understood that this embodiment is merely for the purpose of illustration and description and that various other forms may be devised within the scope of my invention, as defined in the appended claims.

I claim:

1. The method of producing ingots of rising or open steel, which includes teeming the said steel into a vertical ingot mold having a vertical top opening, continuing the teeming until the level of the said steel is adjacent the said opening, disposing over the said opening a cover plate of sufficient area to cover the same, said cover plate being provided with a depending inverted frusto-conical member of sufficient length to extend

downwardly into adjacency with the upper portions of the side walls of the mold and into chilling contact with the steel, whereby a fin is formed between the inverted frusto-conical member and the adjacent upper portions of the side walls of the mold, thereby enabling a locking action to be effected by the tilting of the said member.

2. The method of producing ingots of rising or open steel which includes teeming the said steel into a vertical ingot mold having a vertical top opening, continuing the teeming until the level of the said steel is adjacent the said opening, disposing over the said opening a cover plate of sufficient area to cover the same, said cover plate being provided with a depending inverted frusto-conical member of sufficient length to extend downwardly into adjacency with the upper portions of the side walls of the mold and into chilling contact with the steel, whereby a fin is formed between the inverted frusto-conical member and the adjacent upper portions of the side walls of the mold, thereby enabling a locking action to be effected by the tilting of the said member, said member having an imperforate concave bottom adapted to receive the upper surface of the steel immediately preparatory to chilling the same.

3. The method of producing ingots of rising or open steel, which includes teeming the said steel into a vertical ingot mold having a top opening with substantially vertical sides, continuing the teeming until the level of the said steel is adjacent the said opening, disposing over the said opening a cover plate of sufficient area to cover the same, said cover plate being provided with a depending inverted frusto-conical member of sufficient length to extend downwardly into adjacency with the upper portions of the vertical sides of the top opening of the mold and into chilling contact with the steel, whereby the steel in the space between the inverted frusto-conical member and the adjacent substantially vertical sides of the top opening forms an inverted V-shaped fin, thereby enabling a locking action to be effected by the tilting of the said member.

4. The method of producing ingots of rising or open steel, which includes teeming the said steel into a vertical ingot mold having a top opening with substantially vertical sides, continuing the teeming until the level of the said steel is adjacent the said opening, disposing over the said opening a cover plate of sufficient area to cover the same, said cover plate being provided with a depending inverted frusto-conical member of sufficient length to extend downwardly into adjacency with the upper portions of the vertical sides of the top opening of the mold and into chilling contact with the steel, whereby the steel in the space between the inverted frusto-conical member and the adjacent substantially vertical sides of the top opening forms an inverted V-shaped fin, thereby enabling a locking action to be effected by the tilting of the said member, said member having an imperforate concave bottom adapted to receive the upper surface of the steel immediately preparatory to chilling the same.

EDGAR MARBURG.
